TRANSFER MEANS FOR THERMOPLASTIC CAPS, HAVING MEANS TO HEAT SAID CAPS DURING TRANSFER

Edward Vantlander, Astoria, N. Y., assignor to American Seal-Kap Corporation of Delaware, Wilmington, Del., a corporation of Delaware

Application March 31, 1949, Serial No. 84,719

14 Claims. (Cl. 226—88.1)

1

This invention relates to a machine for applying flexible skirted hood caps to the mouth of milk bottles. It is especially adapted for applying and sealing hood caps having a pleated skirt which is in whole or in part coated with a thermoplastic adhesive which requires heat and pressure for sealing it about the mouth and pouring lip of a milk bottle. Such a cap is shown and described in Patent No. 2,325,168 issued on July 27, 1943, to the American Seal Kap Corporation of Delaware on an application of Herbert G. Vore.

This machine is especially adapted for use in smaller dairies whose total volume of business is such that it does not justify the installation of one of the more complicated and expensive high speed machines of this type which is available today.

The principal object of the invention is to provide a simple and efficient machine of this type which is relatively cheap to manufacture and which can be used in conjunction with standard filling and capping machines in use at the present time.

Another object of the invention is to provide novel and improved means for heating the skirts of the caps in order to soften the adhesive applied thereto.

Still another object of the invention is to provide novel and efficient means for successively withdrawing caps from the bottom of a stack of nested caps, of the aforesaid type, and presenting them to the heating means for sufficient time to render the thermoplastic adhesive thereon soft and tacky, and then discharging the caps in a chute by which they are conveyed to a capping station.

Another object of the invention is to provide a machine of this character which is driven directly from the filling and capping machine with which it is associated.

A further object of the invention is to provide an improved suction head by which the caps are grasped and withdrawn from the stack.

Other and more limited objects of the invention will be apparent from following the specification and the accompanying drawings forming a part thereof wherein:

Fig. 1 is a horizontal section taken on the line 1—1 of Fig. 2 showing my improved machine associated with a standard filling and capping machine which is shown somewhat diagrammatically in top plan;

Fig. 2 is a side elevation of my machine, parts thereof being broken away for the purpose of illustration;

2

Fig. 3 is an enlarged sectional end elevation as viewed from the line 3—3 of Fig. 2;

Fig. 4 is an enlarged substantially vertical section taken on the line 4—4 of Fig. 2;

5 Fig. 5 is a central vertical section taken on the line 5—5 of Fig. 3;

Fig. 6 is a horizontal section taken on the line 6—6 of Fig. 2;

10 Fig. 7 is a detail section taken on the line 7—7 of Fig. 2;

Fig. 8 is an edge view of the cap chute with the lower end thereof in section to show the cap supporting and applying means;

15 Fig. 9 is a vertical section taken on the line 9—9 of Fig. 8;

Fig. 10 is a horizontal section taken on the line 10—10 of Fig. 8; and

Fig. 11 is a central vertical section through one of the suction heads.

20 In Figs. 1 and 2 of the drawings I have shown my improved machine applied to a standard filling and capping machine which includes a filling tank 1 which is rotatably supported above a base 2. Between the tank 1 and the base 2 are

25 a plurality of stools 3 which are suitably mounted upon a rotatable turret which is adapted to be rotated in unison with the tank 1. A plurality of filling valves are carried by and extend downwardly from the tank 1 in alignment with the stools 3. Empty bottles are delivered to the filler by a conveyor 4. As the bottles are delivered they are successively transferred from the conveyor 4, by a rotating star wheel 5, onto successive stools as they move past the star wheel

35 5. As the bottles are carried around on the stools 3 the stools are elevated to raise the bottles up into engagement with the filling valves through which the bottles are filled as they travel around on the stools. After the bottles have been filled

40 the stools are lowered and the filled bottles are then successively transferred by a star wheel 6 onto stools 7 mounted on a rotating turret beneath suitable capping heads. After the bottles have been capped they are transferred from the

45 stools 7 back onto the conveyor 4 by which they are carried away. The star wheel 5 is mounted upon a shaft 8 and all of the various elements are operated in unison by suitable mechanism mounted in the base 2.

50 My improved apparatus includes an upwardly extending standard to the upper end of which is secured a horizontally extending arm. The standard may be secured to a suitable base or may be bolted to the filling and capping machine as desired. Supported by the horizontal arm are a

cap reservoir adapted to hold a stack of caps, a heating mechanism by which the caps are heated until the thermoplastic adhesive thereon becomes soft and tacky in condition to be sealed over and about the mouths and pouring lips of bottles, a cap supporting and applying means, a chute by which heated caps are delivered to the cap supporting and applying means and a transfer mechanism by which caps are successively withdrawn from the reservoir and conveyed through the heating mechanism and then deposited in the chute.

The transfer mechanism comprises a rotating hub to which are secured three equally spaced radially extending hollow arms. A suction head is slidably mounted on the outer end of each of the arms. The transfer mechanism is arranged to successively move the suction heads under and past the reservoir. As each suction head comes under the reservoir it is automatically elevated by a pair of suitable cams into engagement with the bottom cap in the reservoir which is grasped and removed from the stack. After being withdrawn from the reservoir the cap is conveyed through an arcuate shaped heating chamber where it is heated by an electrical resistance element until the thermoplastic adhesive thereon becomes soft and tacky. After leaving the heating chamber the cap is deposited in a hopper secured to the upper end of the delivery chute. In the hopper the cap is turned edgewise after which it drops into the delivery chute which conveys it to the cap supporting and applying means secured to the lower end of the chute. The cap supporting and applying means is disposed in the path of the filled bottles, as they are transferred from the stools 3 of the filler to the stools 7 of the capper, in position for the top of successive bottles to engage and withdraw successive caps therefrom as the bottles move thereby. The cams by which the suction heads are elevated into engagement with a cap in the reservoir are moved from an inoperative position to an operative position by a suction operated piston in a suitable cylinder mounted upon the horizontal arm. The operation of the piston is controlled by the filled bottles passing a predetermined point as they are being filled. At this point there is a valve having an operating handle which projects into the path of the bottles being filled. The valve is located in the suction line between the source of suction and the cylinder on the horizontal arm. As a bottle engages the operating handle it moves it to momentarily open the valve. Suction is then applied to the cylinder causing the piston therein to move downwardly. The downward movement of the piston elevates the cams into position to raise a suction head into position to withdraw a cap from the reservoir. The valve is so located with respect to the capping station that it takes a bottle substantially the same amount of time to travel from the valve to the cap applying station as it takes a cap to be withdrawn from the reservoir heated and delivered to the cap supporting and applying means at the capping station. With this arrangement each bottle initiates the release of its own cap. If a bottle is missing in the regular succession of bottles travelling to the cap applying station then a corresponding cap will be missing in the regular succession of caps travelling to the capping station to meet the bottles. The transfer mechanism is driven through suitable connections from the shaft 8 on which the star wheel 5 is mounted. Suction is applied to the

cylinder and to the suction heads by a vacuum pump and suitable conduits.

After the bottles leave the capping station with caps loosely applied to the mouths and pouring lips thereof they are positioned upon the stools 7 of the capping mechanism under suitable capping heads. The capping heads force the caps fully into the mouths of the bottles and clamp and hold the skirts about the pouring lips of the bottles until the thermoplastic adhesive cools and hardens firmly securing the caps in place. Such an arrangement is shown in the patent to Goodwin et al. No. 2,325,163, issued July 27, 1943.

Referring now to the drawings by reference characters, the numeral 10 indicates an upwardly extending standard which may have the lower end thereof secured to a suitable base or bolted to the filling and capping machine as desired. Secured to the upper end of this standard 10 is a horizontally extending arm 11, which during operation projects over the filling and capping mechanism. A brace 12 between the standard 10 and arm 11 is provided for strengthening purposes. A pair of spaced wedge-shaped supports 13 are secured to and extend upwardly from the free end of the arm 11, one at each side thereof. A cover plate 13a is secured to the upper edge of the supports 13 and extends therebetween. The forward end of the plate 13a is secured to and supported by a pair of plates 13b extending upwardly from the arm 11. Secured to and extending upwardly from the plate 13a is a pair of spaced parallel frame members 14 and 15. A pair of identical spaced parallel supporting bars 16 are suitably secured, as by welding, to the rear edges of the supporting frames 14 and 15. The bars 16 extend up beyond the upper ends of the frame members 14 and 15 a short distance where they are bent at right angles as indicated at 17 and then extend forwardly over the upper ends of the frame members 14 and 15 in alignment therewith. The upper ends 17 of the bars 16 each has a bore 18 therein. Removably mounted in the bores 18 is a pair of identical rods 19 which extend upwardly from the ends 17 of the bars 16 and support therebetween a cap reservoir 20 to which the upper ends 21 of the rods are welded as indicated at 22. The cap reservoir consists of an open-ended tube, the lower end 23 of which is disposed a short distance above the forwardly extending ends 17 of the rods 16.

A cap support generally indicated by the numeral 24 is slidably supported (for the purpose to be described) between the bar ends 17 by bosses 25 which are formed integral with the cap support and have bores 26 through which the bar ends 17 extend. The bores 26 are made considerably larger than the bar ends 17 in order that the cap support 24 may slide freely without danger of binding. The rearward movement of the cap support 24 is limited by stop pins 27 projecting outwardly from the bar ends 17, and the forward movement is limited by the upward extensions of the rods 19. The cap support 24 comprises a split ring 28 having the opposed ears 29 and 30. A screw 31 which extends freely through a smooth aperture in the ear 29 is screwed into a threaded aperture in the ear 30. A coil spring 32 is disposed about the screw 31 between the ears 29 and 30. The screw 31 and spring 32 are provided to adjust the diameter of the ring 28. A pair of arcuate opposed jaws 33 having downwardly and inwardly inclined surfaces 34 are formed integral with and extend downwardly from the lower edge of the ring 28,

one at each side thereof, as clearly shown in Figs. 2, 4 and 7. The jaws 33 are adapted to support a stack 35 of nested inverted caps which extends downwardly from the reservoir 29, through the lower end 23 thereof, into engagement with the jaws.

A hub 36 is rotatably mounted between the frames 14 and 15 upon a stud 37 which is rigidly secured to the frame 15 as indicated at 38. The hub 36 has a reduced end 39 which extends through and bears in a cylindrical bore 40 in the frame 14. A sprocket 41 is keyed to the reduced end 39 and is held thereon by a nut 42. Three equally spaced radially extending hollow arms 43 are secured to the hub 36 midway between the side frames 14 and 15. Slidably mounted upon each arm 43 is a sleeve 44 each of which has secured to the outer end thereof a suction head generally indicated by the numeral 45. During operation the hub 36 is continuously rotated through the sprocket 41 by a chain 46 which is driven by a sprocket 47 mounted on one end of a rotating shaft 48 which is mounted in suitable bearing carried by the wedge-shaped supports 13. A bevel gear 49 is secured to the other end of the shaft 48. The bevel gear 49 meshes with a bevel gear 50 secured to the upper end of a vertical shaft 51. The shaft 51 is rotated by the shaft 8, of the filling machine, through a connecting shaft 52 and a pair of universal joints 53.

Each suction head 45 comprises a base 55 having two spaced annular flanges 56 and 57 extending outwardly therefrom and providing therebetween an annular recess 58 in which is seated a sponge rubber gasket 59. The base 55 is secured to the outer end of a sleeve 44 and has two spaced longitudinal bores 60 and 61 therein which are connected by a transverse bore 62. The bores 60, 61 and 62 provide a communicating passageway between the interior of the sleeve 44 and arm 43 and the annular chamber 63 defined by the annular flange 57. An axially aligned recess 64 in the base 55 intersects the transverse bore 62. A valve plunger 65 having an annular groove 66 is slidably mounted in the recess 64. The valve plunger 65 has a stem 67, of reduced diameter, which extends out from the recess 64 into a cup-shaped member 68 which is shown as formed integral with a plate 69 which is secured to the base 55 within the chamber 63 by screws 70. A disc 71 is pinned to the outer end of the stem 67, and a coil spring 72 is disposed about the stem 67 between the disc 71 and the plate 69. The spring 72 normally urges the valve plunger outwardly until the shoulder formed between the stem 67 and the valve plunger 65 engages the back of the plate 69 which prevents further outward movement. In this position the annular groove 66 is out of register with the bore 62 and communication between the interior of the sleeve 44 and the chamber 63 is cut off. But when the suction head is raised to remove a cap from the bottom of the stack 35, as will be hereinafter described, the valve stem and plunger are depressed, bringing the groove 66 into register with the transverse bore 62 establishing communication between the chamber 63 and the interior of the sleeve 44 and arm 43. The base 55 of the suction head 45 carries a pair of rollers 75 which are rotatably mounted upon suitable axially aligned studs 76 secured to and projecting outwardly from the base 55. The sleeves 44, which are slidably mounted on the arms 43 for radial movement, are prevented from turning on the

arms 43 by pins 77 which are secured to the arms 43 and extend through elongated slots 78 in the sleeves 44. The sleeves 44 are normally urged radially inwardly by springs 79 which have one end thereof connected to the pins 77 and the other end thereof connected to pins 80 carried by the bases 55.

The stud 37 has an axial bore 85 therein. The inner end of the bore 85 is connected by a transverse bore 86 to an annular groove 87 which is formed in and extends partially around the stud 37. The outer end of the bore 85 is connected by a coupling 88 to a tube 89 which leads to a vacuum pump (not shown). The stud 36 also has a longitudinal groove 90 formed in the periphery thereof, the outer end of which is open to the atmosphere as indicated at 91. Radial bores 36a disposed in axial alignment with the hollow arms 43 provide communication first between the interior of the arms 43 and the annular groove 87, and then between the arms 43 and the longitudinal groove 90.

A pair of similar cams generally indicated by the numeral 95 are slidably mounted against the inner walls of the frames 14 and 15 adjacent the upper ends thereof. Each cam 95 comprises a base 96 having an outwardly extending rib 97 and an upwardly extending arm 98 thereon. The ribs 97 are slidably mounted in elongated slots 99 through the frames 14 and 15, and are held therein by plates 100 which are secured thereto. The arms 98 have upwardly and forwardly inclined cam surfaces 98a formed along the rear thereof. The cams 95 are normally urged downwardly in the slots 99 by springs 101, and are raised at predetermined times by rocker arms 102 which are pivotally mounted upon studs 103 secured to the frames 14 and 15. The upward movement of the cams 95 is limited by adjustable stop screws 94 extending down into the slots 99 in position to engage the upper ends of the ribs 97.

One end of each of the rocker arms 102 engages a shoulder 104 on each of the cam arms 98 opposite the cam surfaces 98a. The other ends of the rocker arms 102 are connected by a pair of links 105 to a cross-head 106 which is secured to the outer end of a piston rod 107, the inner end of which is secured to a piston 108 slidably mounted in a cylinder 109. The cylinder 109 is secured by bolts 110 to the underside of the cover plate 13a, between the wedge-shaped supports 13, and a pair of plates 13b which support the forward upper end of the plate 13a. The lower end of the cylinder 109 is connected to the vacuum pump previously referred to by a conduit 111. When vacuum is applied to the cylinder 109 beneath the piston 108, the piston 108 therein and the piston rod 107 and crosshead 106 connected to the piston 108 will be drawn downwardly. The downward movement of the crosshead 106 through the links 105 will rock the rocker arms 102 which in turn will raise the cams 95 to their uppermost position, as determined by the stops 94, for a purpose to be hereinafter described. The operation of the piston 108 and consequently the raising and lowering of the cams 95 is controlled by a three-way valve 112 which is interposed in the conduit 111 between the cylinder 109 and the vacuum pump, and is adapted to alternately connect the cylinder 109 to vacuum and to atmosphere. After suction to the cylinder 109 has been cut off and the cylinder vented to the atmosphere, the piston 108 and parts carried thereby are returned to their initial position by a compression spring 113 disposed

about the piston rod 101 between the plate 13a and the crosshead 106. The valve 112 which is mounted at a predetermined location on the filling machine has an operating handle 114 which projects into the path of the bottle and is adapted to be successively engaged by the bottles as they are being filled. Each bottle as it engages the handle 114 operates the valve to connect the cylinder 109 to the source of vacuum. After a bottle passes the handle 114 the valve is returned to its initial position, venting the cylinder 109 to atmosphere by suitable spring means, not shown.

As the suction heads 45 are moved along their orbital path by the rotation of the hub 36, they pass through a heating chamber generally indicated by the numeral 120. The heating chamber 120 comprises a pair of spaced side walls 121, which are secured to and straddle the frames 14 and 15, and an arcuate peripheral wall 122. A plurality of insulating spools 123 are secured to the peripheral wall 122 in spaced relation within the chamber 120, and support thereon an electrical resistance heating element 124, which are adapted to radiate heat radially inwardly when energized.

A hopper 126 having a pair of spaced upwardly extending side walls 127 secured to the opposed faces of the frames 14 and 15 is mounted adjacent the lower rear end of the heater 120. The hopper 126 is connected to and discharges into the upper end of a downwardly and rearwardly inclined chute 128, the lower end of which is connected to a vertical chute 129 supported by a bracket 130 secured to and extending rearwardly from the horizontal arm 11. A cap deflector plate 131 is connected to one of the walls 127 of the hopper and inclines inwardly and downwardly into the hopper, and a cap-supporting and applying means is mounted in the lower end of the vertical chute 129.

The cap supporting and applying means, generally indicated by the numeral 135, comprises a pair of spaced supports 136 each having a downwardly and inwardly inclined surface 137 which are adapted to engage the lower peripheral edge of a cap and support the cap in a vertical position at the lower end of the chute 129 as shown in Figs. 8, 9 and 10. The supports 136 are secured to the side walls 138 of the chute 129 at the lower open end thereof, and each has a forwardly extending arm 139 secured to the lower end thereof below the inclined surface 137, along which the caps slide as they are being withdrawn from the support by moving bottles. The front wall 140 of the chute terminates a substantial distance above the lower end of the chute as indicated at 141, and the rear wall 142 is cut out as indicated at 143 to provide for the passage of the neck of a bottle between the side walls 138 and the supports 136. A gate 144 which is pivotally secured to the lower end of the front wall 140, as indicated at 145, extends downwardly and forwardly from the lower edge 141 thereof into the path of caps as they are being withdrawn from the supports 136 by the bottles. The gate 144 is yieldingly held in the position shown in Figs. 2 and 8 by a spring 146, and is provided to assure the tipping of the caps onto the mouth of bottles as they are being withdrawn from the supports 136 along the arms 139.

In operation the apparatus is mounted adjacent a filling and capping machine with the cap supporting and applying mechanism 135 disposed in the path of the filled bottles along which they are moved as they are being transferred

from the filling mechanism to the capping mechanism by the star wheel 6, and with the shaft 51 connected to the shaft 8, which drives the star wheel 5, by the connecting shaft 52 and the universal joint 53. Then when the filling and capping mechanisms are operating the hub 36, and the arms 43 and suction heads 45 carried thereby, are operated in unison with the filling and capping mechanisms. As the bottles are carried around on the stools 3 while being filled, they successively engage the operating handle 114 of the valve 112 and momentarily open the valve 112 which applies suction to the cylinder 109 beneath the piston 108. After each bottle passes the handle 114 the valve 112 returns to its initial position, cutting off suction to the cylinder 109 and venting it to atmosphere. The application of suction to the cylinder 109 moves the piston 108 therein downwardly which rocks the rocker arms 102 and raises the cam 95 into position for the cam surfaces 98a to be engaged by the rollers 75 on the suction heads 45 as the heads are carried around by the hub 36 and the arms 43. After the rollers engage the cam surfaces 98a the continued movement of the heads causes the cams 95 to raise the heads into engagement with the bottom cap of the stack 35 of nested caps. The arrangement and timing of the apparatus is such that the cams 95 are raised just prior to the engagement of the rollers 75 therewith. As the suction heads engage the bottom cap of the stack the valve plungers 65 therein are depressed which opens the passage between the interior of the hollow arms 43 and the chambers 63 in the heads. Suction is then applied to the chambers 63 through the tube 85, bores 85 and 86, annular groove 87, radial bores 36a, hollow arms 43 and the passageways in the heads 45 between the chambers 63 and the interior of the arms 43. The bottom caps of the stack 35 will then be suctionally gripped and held firmly against the sponge rubber gaskets 69 carried by the heads. Then upon further movement of the suction heads the stack support will be moved forwardly and upwardly to the position shown in dotted lines in Fig. 5, after which the bottom caps are withdrawn from between the jaws 33 and carried through the heating chamber 120. While travelling through the heating chamber the caps are heated until the thermoplastic adhesive on the skirts thereof becomes soft and tacky in condition for securely sealing the caps over and about the mouth and pouring lips of bottles. As the suction heads and caps thereon leave the heating chamber 120, they pass over the hopper 126 between the upwardly extending sides 127 thereof. At this point the radial bores 36a pass out of communication with the annular groove 87 and into communication with the longitudinal groove 90 which cuts off the suction to the chamber 63 and vents it to atmosphere thus releasing the caps and allowing them to drop into the hopper 126. The caps fall from the hopper 126 into the chute 128 past the deflector plate 131 which turns the caps to an edgewise position as they enter the chute 128. The caps then roll down the inclined chute 128 into the vertical chute 129 and drop onto the supports 136 in position to be engaged by the necks of bottles moving past the bottom of the vertical chute 129 and between the supports 136. As the caps are withdrawn from the chute they are deposited loosely over and about the mouths and pouring lips of the bottles. The bottles are then moved onto the stools 7 beneath suitable capping heads which

press the caps firmly onto the bottles and clamp and hold the cap skirts about the necks of the bottles until the thermoplastic adhesive on the cap skirts cools and hardens securely holding the caps in place.

From the foregoing it will be apparent that I have provided a very simple and efficient apparatus for carrying out the objects of my invention.

It is to be understood that I am not limited to the specific construction shown and described herein as various modifications can be made thereto within the spirit of the invention.

What is claimed is:

1. In a device of the character described, the combination of a downwardly inclined reservoir adapted to hold a stack of inverted nested caps having a thermoplastic adhesive applied to the skirts thereof, a heating chamber in which the caps are heated until the thermoplastic adhesive thereon becomes soft and tacky in condition for sealing the caps over and about the mouth and pouring lips of bottles, a cap supporting and applying means adapted to be disposed in the path of filled bottles being transferred from a filling mechanism to a capping mechanism, a chute by which heated caps are delivered to said cap supporting and applying means, and a cap transfer mechanism operative to successively withdraw caps from the bottom of said stack of nested caps and carry said caps through said heating chamber and then deposit said caps in said chute for delivery to said cap supporting and applying means, said transfer mechanism comprising a hub rotatably mounted about a horizontal axis, a plurality of radially extending arms secured to said hub, a suction head slidably mounted on the outer end of each of said arms, means for rotating said hub to move successive suction heads successively under said stack of caps through said heating chamber and over the upper end of said chute, and means operative to shift said suction heads on said arms into engagement with the bottom cap of said stack as they pass thereunder.

2. In a device of the character described, the combination of a downwardly inclined reservoir adapted to hold a stack of inverted nested caps having a thermoplastic adhesive applied to the skirts thereof, a heating chamber in which the caps are heated until the thermoplastic adhesive thereon becomes soft and tacky in condition for sealing the caps over and about the mouths and pouring lips of bottles, a cap supporting and applying means adapted to be disposed in the path of filled bottles being transferred from a filling mechanism to a capping mechanism, a chute by which heated caps are delivered to said cap supporting and applying means, and a cap transfer mechanism operative to successively withdraw caps from the bottom of said stack of nested caps and carry said caps through said heating chamber and then deposit said caps in said chute for delivery to said cap supporting and applying means, said transfer mechanism comprising a hub rotatably mounted about a horizontal axis, a plurality of radially extending arms secured to said hub, a suction head slidably mounted on the outer end of each of said arms, means for rotating said hub to move successive suction heads successively under said stack of caps through said heating chamber and over the upper end of said chute, means for elevating said suction heads into engagement with the bottom cap of said stack of caps as they pass thereunder,

means to apply suction to said suction head as they engage said bottom caps to cause said suction heads to suctionally hold and withdraw said bottom caps from said stack, and means for causing said suction heads to release said caps when said suction heads are over said chute.

3. In a device of the character described, the combination of a downwardly inclined reservoir adapted to hold a stack of inverted nested caps having a thermoplastic adhesive applied to the skirt thereof, a heating chamber in which the caps are heated until the thermoplastic adhesive thereon becomes soft and tacky in condition for sealing the caps over and about the mouths and pouring lips of bottles, a cap supporting and applying means adapted to be disposed in the path of filled bottles being transferred from a filling mechanism to a capping mechanism, a chute by which heated caps are delivered to said cap supporting and applying means, and a cap transfer mechanism operative to successively withdraw caps from the bottom of said stack of nested caps and carry said caps through said heating chamber and then deposit said caps in said chute for delivery to said cap supporting and applying means, said transfer mechanism comprising a hub rotatably mounted about a horizontal axis, a plurality of radially extending arms secured to said hub, a suction head slidably mounted on the outer end of each of said arms, means for rotating said hub to move successive suction heads successively under said stack of caps through said heating chamber and over the upper end of said chute, cam means adapted to be engaged by successive suction heads and operative to elevate said suction heads into engagement with the bottom cap of said stack of caps, means to apply suction to said suction heads as they engage said bottom caps to cause said suction heads to suctionally hold and withdraw said bottom caps from said stack, and means for causing said suction heads to release said caps when said suction heads are over said chute.

4. In a device of the character described, the combination of a downwardly inclined reservoir adapted to hold a stack of inverted nested caps having a thermoplastic adhesive applied to the skirt thereof, a heating chamber in which the caps are heated until the thermoplastic adhesive thereon becomes soft and tacky in condition for sealing the caps over and about the mouths and pouring lips of bottles, a cap supporting and applying means adapted to be disposed in the path of filled bottles being transferred from a filling mechanism to a capping mechanism, a chute by which heated caps are delivered to said cap supporting and applying means, and a cap transfer mechanism operative to successively withdraw caps from the bottom of said stack of nested caps and carry said caps through said heating chamber and then deposit said caps in said chute for delivery to said cap supporting and applying means, said transfer mechanism comprising a hub rotatably mounted about a horizontal axis, a plurality of radially extending arms secured to said hub, a suction head slidably mounted on the outer end of each of said arms, means for rotating said hub to move successive suction heads successively under said stack of caps through said heating chamber and over the upper end of said chute, cam means mounted for sliding movement between operative and inoperative positions and adapted when in operative position to be engaged by successive suction heads and operative to elevate said suc-

tion heads into engagement with the bottom cap of said stack of caps, means to apply suction to said suction heads as they engage said bottom caps to cause said suction heads to suctionally hold and withdraw said bottom caps from said stack, and means for causing said suction heads to release said caps when said suction heads are over said chute.

5. In a device of the character described, the combination of a downwardly inclined reservoir adapted to hold a stack of inverted nested caps having a thermoplastic adhesive applied to the skirt thereof, a heating chamber in which the caps are heated until the thermoplastic adhesive thereon becomes soft and tacky in condition for sealing the caps over and about the mouths and pouring lips of bottles, a cap supporting and applying means adapted to be disposed in the path of filled bottles being transferred from a filling mechanism to a capping mechanism, a chute by which heated caps are delivered to said cap supporting and applying means, and a cap transfer mechanism operative to successively withdraw caps from the bottom of said stack of nested caps and carry said caps through said heating chamber and then deposit said caps in said chute for delivery to said cap supporting and applying means, said transfer mechanism comprising a hub rotatably mounted about a horizontal axis, a plurality of radially extending arms secured to said hub, a suction head slidably mounted on the outer end of each of said arms, means for rotating said hub to move successive suction heads successively under said stack of caps through said heating chamber and over the upper end of said chute, cam means mounted for sliding movement between operative and inoperative positions and adapted when in operative position to be engaged by successive suction heads and operative to elevate said suction heads into engagement with the bottom cap of said stack of caps, means responsive to the passage of bottles past a given point for moving said cam means from inoperative to operative position, means to apply suction to said suction heads as they engage said bottom caps to cause said suction heads to suctionally hold and withdraw said bottom caps from said stack, and means for causing said suction heads to release said caps when said suction heads are over said chute.

6. In a device of the character described, the combination of a downwardly inclined reservoir adapted to hold a stack of inverted nested caps having a thermoplastic adhesive applied to the skirt thereof, a heating chamber in which the caps are heated until the thermoplastic adhesive thereon becomes soft and tacky in condition for sealing the caps over and about the mouths and pouring lips of bottles, a cap supporting and applying means adapted to be disposed in the path of filled bottles being transferred from a filling mechanism to a capping mechanism, a chute by which heated caps are delivered to said cap supporting and applying means, and a cap transfer mechanism operative to successively withdraw caps from the bottom of said stack of nested caps and carry said caps through said heating chamber and then deposit said caps in said chute for delivery to said cap supporting and applying means, said transfer mechanism comprising a hub rotatably mounted about a horizontal axis, a plurality of radially extending arms secured to said hub, a suction head slidably mounted on the outer end of each of said arms, means for rotating said hub to move successive suction heads successively under said stack of caps through said heating chamber and over the upper end of said chute, and means operative to elevate said suction heads into engagement with the bottom cap of said stack as they pass thereunder.

suction heads successively under said stack of caps through said heating chamber and over the upper end of said chute, cam means mounted for sliding movement between operative and inoperative positions and adapted when in operative position to be engaged by successive suction heads and operative to elevate said suction heads into engagement with the bottom cap of said stack of caps, a rocker arm having one end thereof operatively connected to said cam means and the other end thereof connected to a pressure operated piston, means for applying pressure to said piston to cause it to rock said rocker arm and move said cam means from inoperative to operative position, means to apply suction to said suction heads as they engage said bottom caps to cause said suction heads to suctionally hold and withdraw said bottom caps from said stack, and means for causing said suction heads to release said caps when said suction heads are over said chute.

7. In a device of the character described, the combination of a downwardly inclined reservoir adapted to hold a stack of inverted nested caps having a thermoplastic adhesive applied to the skirt thereof, a heating chamber in which the caps are heated until the thermoplastic adhesive thereon becomes soft and tacky in condition for sealing the caps over and about the mouths and pouring lips of bottles, a cap supporting and applying means adapted to be disposed in the path of filled bottles being transferred from a filling mechanism to a capping mechanism, a hopper into which heated caps are deposited, a chute connected to said hopper by which caps are conveyed from said hopper to said cap supporting and applying means, cap tilting means within said chute by which caps are turned to an edgewise position as they pass from said hopper into said chute, and cap transfer mechanism operative to successively withdraw the bottom cap from said stack of nested caps and carry said caps through said heating chamber and then deposit them in said hopper, said transfer mechanism comprising a hub rotatably mounted about a horizontal axis, a plurality of radially extending arms secured to said hub, a suction head slidably mounted on the outer end of each of said arms, means for rotating said hub to move successive suction heads successively under said stack of caps through said heating chamber and over the upper end of said chute, and means operative to elevate said suction heads into engagement with the bottom cap of said stack as they pass thereunder.

8. In a device of the character described the combination of a cap reservoir adapted to hold a stack of inverted nested caps having a thermoplastic adhesive applied to the skirts thereof, said stack extending down below the lower open end of said reservoir a substantial distance, stack supporting means disposed below the lower end of said reservoir in position to releasably engage the bottom cap of said stack, said stack supporting means being slidably supported on suitable guides and adapted to be moved forwardly on said guides as caps are successively withdrawn from the bottom of said stack, a heating chamber in which the caps are heated until the thermoplastic adhesive thereon becomes soft and tacky in condition for sealing the caps over and about the mouths and pouring lips of bottles, a cap supporting and applying means adapted to be disposed in the path of filled bottles being transferred from a filling mechanism to a capping

mechanism, a chute by which heated caps are delivered to said cap supporting and applying means, and a cap transfer mechanism operative to successively withdraw caps from the bottom of said stack of nested caps and carry said caps through said heating chamber and then deposit said caps in said chute for delivery to said cap supporting and applying means, said transfer mechanism comprising a hub mounted for rotation about a horizontal axis, a radially extending arm secured to said hub, a suction head mounted upon the outer end of said arm, means for rotating said hub to successively move said suction head under said stack supporting means through said heating chamber and over the upper end of said chute, and means operative to cause said suction head to engage and withdraw the bottom cap of said stack of caps from said stack supporting means and deposit said bottom cap in said chute after said suction head has passed through said chamber.

9. In a device of the character described, the combination of a downwardly inclined reservoir adapted to hold a stack of inverted nested caps having a thermoplastic adhesive applied to the skirt thereof, a heating chamber in which the caps are heated until the thermoplastic adhesive thereon becomes soft and tacky in condition for sealing the caps over and about the mouths and pouring lips of bottles, a cap supporting and applying means adapted to be disposed in the path of filled bottles being transferred from a filling mechanism to a capping mechanism, a chute by which heated caps are delivered to said cap supporting and applying means, and a cap transfer mechanism operative to successively withdraw caps from the bottom of said stack of nested caps and carry said caps through said heating chamber and then deposit said caps in said chute for delivery to said cap supporting and applying means, said transfer mechanism comprising a hub mounted for rotation about a horizontal axis, a radially extending arm secured to said hub, a suction head mounted upon the outer end of said arm, means for rotating said hub to successively move said suction head under said reservoir through said heating chamber and over the upper end of said chute, means operative to shift said suction head on said arm into engagement with the bottom cap of said stack, a holder carrying the lower caps of said stack, and means mounting said holder to slide in the direction of advance of said head as the head passes said stack in its rotation.

10. In a device of the character described, the combination of a downwardly inclined reservoir adapted to hold a stack of inverted nested caps having a thermoplastic adhesive applied to the skirt thereof, a heating chamber in which the caps are heated until the thermoplastic adhesive thereon becomes soft and tacky in condition for sealing the caps over and about the mouths and pouring lips of bottles, a cap supporting and applying means adapted to be disposed in the path of filled bottles being transferred from a filling mechanism to a capping mechanism, a chute by which heated caps are delivered to said cap supporting and applying means, and a cap transfer mechanism operative to successively withdraw caps from the bottom of said stack of nested caps and carry said caps through said heating chamber and then deposit said caps in said chute for delivery to said cap supporting and applying means, said transfer mechanism comprising a hub mounted for rotation about a horizontal axis, a

radially extending arm secured to said hub, a suction head slidably mounted upon the outer end of said arm, means for rotating said hub to successively move said suction head under said reservoir through said heating chamber and over the upper end of said chute, and means operative to shift said suction head into engagement with the bottom cap of said stack as it passes thereunder said last mentioned means being responsive to the

passage of a bottle past a given point and to the rotation of said hub.

11. In a device of the character described, the combination of a downwardly inclined reservoir adapted to hold a stack of inverted nested caps

having a thermoplastic adhesive applied to the skirt thereof, a heating chamber in which the caps are heated until the thermoplastic adhesive thereon becomes soft and tacky in condition for sealing the caps over and about the mouths and pouring lips of bottles, a cap supporting and applying means adapted to be disposed in the path of filled bottles being transferred from a filling mechanism to a capping mechanism, a chute by which heated caps are delivered to said

cap supporting and applying means, and a cap transfer mechanism operative to successively withdraw caps from the bottom of said stack of nested caps and carry said caps through said heating chamber and then deposit said caps in

30 said chute for delivery to said cap supporting and applying means, said transfer mechanism comprising a hub mounted for rotation about a horizontal axis, a radially extending arm secured to said hub, a suction head mounted upon the outer end of said arm, means for rotating said hub to successively move said suction head under said reservoir through said heating chamber and over the upper end of said chute, means rendered op-

erative by the passage of a bottle past a given point to cause said suction head to engage the bottom cap of said stack of caps, and means rendered operative by the engagement of said suction head with said bottom cap and the rotation of said hub to cause said head to withdraw

45 said bottom cap from said stack of caps and to deposit said bottom cap in said chute after said suction head has passed through said heating chamber.

12. In an apparatus for applying skirted hood caps to bottles having a reservoir adapted to support a stack of nested hood caps and a cap applying mechanism the combination therewith of, a hub mounted for rotation about a horizontal axis,

55 a radially extending arm secured to said hub, a head secured to the outer end of said arm, means for rotating said hub to successively move said head past said reservoir, a cap picker means carried by said head and operative as said head moves past said reservoir to withdraw the end cap from said reservoir for delivery to said cap applying mechanism, a holder carrying the lower caps of said stack, and means mounting said holder to slide in the direction of advance of said

60 head as the head passes said stack in its rotation.

13. In an apparatus for applying skirted hood caps to bottles having a reservoir adapted to support a stack of nested hood caps and a cap applying mechanism the combination therewith of, a hub mounted for rotation about a horizontal axis,

70 a radially extending arm secured to said hub, a suction head secured to the outer end of said arm, means for rotating said hub to successively move said suction head past said reservoir, a normally closed valve in said suction head for

controlling the application of suction to said head, means operative to bring said suction head and the end cap of said stack of caps into engagement with each other as said suction moves past said reservoir, means carried by said suction head which are rendered operative by engagement with said end cap to open said valve to supply suction to said head to withdraw said end cap from said stack for delivery to said cap applying mechanism.

14. In a device of the character described, the combination of a reservoir adapted to hold a stack of nested hood caps, a heating chamber through which caps are conveyed, a cap applying station, a chute by which caps are delivered to said cap applying station, and a transfer mechanism by which caps are successively withdrawn from said reservoir conveyed through said heating chamber and deposited in said chute for delivery to said cap applying mechanism, said transfer mechanism comprising, a hub mounted for rotation about a horizontal axis, a radially extending arm secured to said hub, a sleeve slidably but non-rotatably mounted on said arm, a head secured to the outer end of said sleeve, means for rotating said hub to successively move said head past the discharge end of said reservoir, shiftable cam means adapted when in operative position to be engaged by said head and operative to move said head radially outwardly into engagement with

the end cap of said stack of nested caps, spring means for moving said sleeve and said head radially inwardly after said head has been released by said cam means, picker mechanism carried by said head and operative to withdraw the end cap from said stack of caps and to deposit said end cap in said chute after said head has passed through said heating chamber, and means to shift said cam means from inoperative to operative position in timed relation to the movement of bottles past said cap applying mechanism.

EDWARD VANTLANDER.
